UNITED STATES PATENT OFFICE.

MARY SWEENEY, OF ALLEGHENY, PENNSYLVANIA.

DESIGN FOR A SAD-IRON.

SPECIFICATION forming part of Design No. 31,245, dated July 18, 1899.

Application filed June 24, 1899. Serial No. 721,788. Term of patent 14 years.

To all whom it may concern:

Be it known that I, MARY SWEENEY, a citizen of the United States, residing in Allegheny, county of Allegheny, State of Pennsylvania, have invented and produced a new and useful Design for a Sad-Iron, of which the following is a specification, reference being had to the accompanying drawings, forming part thereof, in which—

Figure 1 is a perspective view of the said sad-iron. Fig. 2 is a top or plan view thereof. Fig. 3 is a side view; and Fig. 4 is a cross-section on the line 4 4, Fig. 3.

As shown in the drawings, the leading and material feature of my design consists in a sad-iron having a long narrow body *a*, provided with a flat base *b* and straight side walls *c*, and having a front end portion *d*, having a convex conical point *e* and a continuously-curved rear end portion *f*, connect-

ing by curved or rounded portions *g* with the straight side walls *c* and having a convex face *h*. The iron has the handle *m*.

The sad-iron is graceful in appearance, while it provides a conical point for entering 25 the smaller gathers or tucks and a continuously-curved rear portion for the larger gathers or ruffles and straight side portions for the ironing of shirts or like flat articles.

What I claim, and desire to secure by Letters Patent, is—

The design for a sad-iron herein shown and described.

In testimony whereof I, the said MARY SWEENEY, have hereunto set my hand.

MARY SWEENEY.
